SHOULDER STRAP SUPPORTER

Willa E. Smith, San Diego, Calif.

Application November 8, 1937, Serial No. 173,493

10 Claims.

(Cl. 24—73)

This invention relates to a shoulder strap supporter for holding and supporting the shoulder strap or straps of lingerie and the like and avoiding the annoyance occasioned by such straps slipping out of place and off the shoulders of the wearer.

One of the objects of this invention is to provide a device of this character wherein the means for securing the device to the garment, is complete in itself, and the necessity of utilizing other means, such as safety pins or the like, for fastening the device to the garment is obviated.

A further object is to provide a device of this character wherein no metal parts whatever contact with the body of the person using the same.

A further object is to provide a device of this character wherein a finger hold or pull is formed on the device itself and the device readily unfastened so as to release the straps.

Heretofore the usual practice has been to permanently attach by stitching or the like, the device to the garment or connect the same to the garment by means of a safety pin or the like, both methods being objectionable in many respects.

In the accompanying drawing wherein similar reference numerals are used to indicate corresponding parts in each of the several views:—

Fig. 1 is a perspective view showing the device as applied in use;

Fig. 2 is a view in side elevation of the device as attached to the garment, the garment being shown in section;

Fig. 3 is a sectional view on the line 3—3 of Fig. 2;

Fig. 4 is a plan view of the device as applied;

Fig. 5 is a view in perspective of the device;

Fig. 6 is a plan view of one side of the device; and

Fig. 7 is a plan view of the opposite side.

The elongated strip or tape 10 has secured thereto one member 11 of a snap fastener a short distance from the free end, the portion of the tape at this end projecting beyond the snap fastener member 11 forming a pull or tab 12, to be used when the device is opened to permit of the removal of the straps.

There is also secured to the tape a complementary member 13 of a snap fastener, a short distance from the member 11. When the two members 11 and 13 are secured together there is formed a loop 14 through which the strap passes and by which it is retained in position on the shoulder of the wearer.

The end of the tape or strip beyond member

13 is formed into a loop 15 the free end of which is secured to the body of the tape by means of the member 13 as at 16.

Both snap members 11 and 13 are arranged on the same side of the strip or tape so that when they are secured together and in use no part of the snap will be in contact with the body of the wearer.

Secured to the tape on each side of the loop 15 is a snap fastener fabric engaging members 17 and 18. These two members are on the opposite side of the tape from snap members 11 and 13 and are adapted to receive between them the inturned portions 19, of the fabric of the garment 20, just below the shoulder seam 21.

The connecting member 22 of the loop portion 15 may of course be dispensed with and the fabric engaging snap members 17 and 18 secured to the two parts 23 and 24 of the tape and equally good results attained.

The manner of using this device will be obvious from the foregoing. The fabric engaging fastening means 17 and 18 are snapped over or through the inturned portions of the garment just below the shoulder seam and the end of the tape carrying the snap member 11 is passed under the shoulder strap and fastened in its cooperating snap member 13. When the device is to be removed from the garment all that is necessary is to take hold of the tab 12 and by a slight pull separate the fastening means which hold the device to the garment. If the device is not to be removed from the garment but simply unfastened so that the straps may be released then the snap members 11 and 13 are separated.

Having thus fully described my invention, what I claim as new and desire to secure by Letters Patent of the United States is:—

1. As an article of manufacture, a shoulder strap supporting device comprising an elongated strip having one member of a snap fastener attached thereto adjacent one end, the other end formed into a loop and secured to the strip by a second snap fastener member, the snap fastener members cooperating with each other and forming a loop through which the shoulder strap passes, a snap fastener member on each side of the end loop, cooperating with each other and adapted to receive between them a portion of the garment for attaching the device to the garment.

2. As an article of manufacture, a shoulder strap supporting device comprising an elongated strip having one member of a snap fastener attached thereto adjacent one end, the other end

- formed into a loop and secured to the strip by a second snap fastener member, the snap fastener members cooperating with each other and forming a loop through which the shoulder strap passes, both snap fastener members being on the same side of the strip, a snap fastener member on each side of the end loop, on the opposite side of the strip, said last mentioned snap members cooperating with each other to receive between them a portion of the garment for attaching the device to the garment.
3. As an article of manufacture, a shoulder strap supporting device comprising an elongated strip having a snap fastener member adjacent one end, the other end formed into an end loop and secured to the strip by a second snap fastener member, the snap fastener members cooperating with each other and forming a loop through which the shoulder strap passes, means on each side of said end loop cooperating to receive between them a portion of the garment for attaching the device to the garment.
4. As an article of manufacture a shoulder strap supporting device comprising an elongated strip having a snap fastener member adjacent one end, said end projecting sufficiently beyond said member to form a finger hold, the other end formed into a loop and secured to the strip by a second snap fastener member, the snap fastener members cooperating with each other and forming a loop through which the shoulder strap passes, a snap fastener member on each side of the end loop, cooperating with each other and adapted to receive between them a portion of the garment for attaching the device to the garment.
5. As an article of manufacture, a shoulder strap supporting device comprising an elongated strip having one member of a snap fastener secured thereto adjacent one end, spaced apart portions at the opposite end, a complemental member of a snap fastener secured to the tape at a point spaced from the first mentioned end, said snap fastener members when connected forming a loop through which the shoulder strap passes, complemental fabric engaging means secured to the strip adjacent the free ends of the spaced apart portions, said last mentioned means when connected receiving between them a portion of the garment for attaching the device to the garment.
6. As an article of manufacture, a shoulder strap supporting device comprising an elongated strip having a snap fastener member adjacent one end, spaced apart portions at the opposite end, a complemental snap fastener member secured to the tape at a point spaced from the first mentioned end, said snap fastener members when connected forming a loop through which the shoulder strap passes, a fabric engaging snap

fastener member adjacent the end of each of said spaced apart portions, said last mentioned members adapted to receive a portion of the garment between them for attaching the device to the garment.

7. As an article of manufacture, a shoulder strap supporting device comprising an elongated strip having one member of a snap fastener adjacent one end, spaced apart portions at the opposite end, a complemental member of a snap fastener secured to the tape at a point spaced from the first mentioned end, said snap fastener members when connected forming a loop through which the shoulder strap passes, a fabric engaging member of a snap fastener adjacent the end of each of said spaced apart portions on the opposite side of the tape when connected adapted to receive a portion of the garment between them for attaching the device to the garment.

8. As an article of manufacture a shoulder strap supporting device comprising an elongated strip, fastening means adjacent one end and a complemental fastening means at a point spaced therefrom, said fastening means when connected forming a loop in the strip through which the shoulder strap passes, complementary fabric engaging fastening means adjacent the opposite end of said strip, spaced apart transversely of the strip, cooperating to receive between them a portion of the garment for removably attaching the device to the garment.

9. As an article of manufacture a shoulder strap supporting device comprising an elongated strip, one end thereof being wider than the other, members of a complemental fabric engaging fastening means secured to and spaced apart on the wider end, said members cooperating with each other to receive between them a portion of the garment for removably attaching the device to the garment, one member of a fastening means secured adjacent the opposite end of said strip and a complemental fastening means secured to said strip at a point spaced therefrom, said fastening members when connected forming a loop through which the shoulder strap passes.

10. As an article of manufacture, a shoulder strap supporting device comprising an elongated strip, transversely spaced apart members of a fabric engaging snap fastening means on said strip adjacent one end thereof adapted to receive between them a portion of the garment and thereby removably attach the device to the garment, a member of a snap fastener adjacent the opposite end, a complemental member of a snap fastener spaced from said end which when connected with the fastener member at the end forms a loop through which the shoulder strap passes.
